R. C. Lankford
(Lawrence Lankford) Witnessess.

UNITED STATES PATENT OFFICE.

JAMES HUTCHISON, OF LANSINGBURG, NEW YORK, ASSIGNOR TO JONATHAN E. WHIPPLE, OF SAME PLACE.

DESIGN FOR FLOOR-CLOTH.

Specification forming part of Design No. 1,706, dated January 27, 1863.

To all whom it may concern:

Be it known that I, JAMES HUTCHISON, of Lansingburg, in the county of Rensselaer and State of New York, have invented or produced a new and original Design for Oil-Cloths; and I do hereby declare that the following is a full, clear, and exact description of the same, reference being had to the accompanying drawing, making a part of this specification, said drawing showing one complete square of the design and four quarter-sections of its adjoining squares.

This design may be described as consisting of outline or skeleton squares formed by a series of rosettes *a* lying adjacent to each other. Within each square there is a square figure *A*, having a single rosette *B* at its center, and just within said figure there is a suc-

cession of lines or stripes *b c d e f g h i*, which correspond to the contour of the figure, except that they are slightly rounded at the corners. The figures *C* shown in the quarter-section have the same contour and the same lines or stripes within as the central one, but the rosette at the center is slightly different.

Having thus described my invention, what I claim as new, and desire to secure by Letters Patent, is—

The specific configuration of the within-described parts to form a new and original design for oil-cloths.

JAMES HUTCHISON.
